UNITED STATES PATENT OFFICE

WILLIAM KREIELSHEIMER, OF NEW YORK, N. Y.

DESIGN FOR A TEXTILE FABRIC

Application filed March 10, 1931. Serial No. 39,019. Term of patent 3½ years.

To all whom it may concern:

Be it known that I, WILLIAM KREIELSHEIMER, a citizen of the United States, residing in Queens County, city of New York, State of New York, whose post-office address is 60 Leonard Street, city of New York, county of New York, and State of New York, have invented a new, original, and ornamental Design for a Textile Fabric, of which the following is a specification, reference being had to the accompanying drawing, forming part thereof.

The figure is a plan view of a textile fabric showing my new design. A single unit of my design is substantially comprised within the area defined by the indicating lines shown on the drawing.

I claim:

The ornamental design for a textile fabric substantially as shown and described.

WILLIAM KREIELSHEIMER.
